Application October 19, 1937, Serial No. 169,850

10 Claims. (Cl. 101—250)

This is a continuation in part of my copending application, Serial No. 134,340, filed April 1, 1937, for type beds.

This invention relates to machine construction and particularly to machines subject to temperature change and utilizing elements composed of different materials having different thermal coefficients of expansion.

In many machines it is desirable for various reasons to construct elements thereof of different materials. This presents no difficulty where the temperature of the machine does not vary materially from time to time. Where a machine is subject to relatively wide temperature variations, however, composite construction wherein the parts are rigidly secured together as by bolts, screws, or the like, frequently causes warping, distortion and similar effects because the thermal coefficients of expansion of the usual materials of construction differ so widely.

I have invented a composite construction which avoids the aforementioned difficulty and permits materials having widely different thermal coefficients to be used in the construction of machines subject to temperature variation, without causing buckling, warping or the like. In accordance with the invention I secure together the parts of a composite member having different coefficients of expansion by means which permits relative movement therebetween. Such means may take a number of forms, typical examples of which will be described in detail below. The examples selected are portions of the type-bed of a bed and cylinder press but it will be understood that this application is chosen only for illustration and that the invention may be applied as well to numerous other machines.

The bed of bed and cylinder presses must be reciprocated forward and backward once for each cycle of the press, i. e., the type-bed must be started from rest, brought up to a linear speed equal to the peripheral speed of the cylinder, maintained at such linear speed during the printing operation, slowed down and brought to rest, and then returned to its original starting position and brought to rest thereat. Thus the inertia of the bed must be overcome in accelerating it, and the momentum overcome in stopping it, twice during each cycle of the press. With this in mind, and in view of the demand for greater and greater press speeds, attempts have been made to reduce the weight of the type-beds while still retaining the strength required for them to resist the heavy strains to which they are subjected. Among these attempts have been pro-

posals to construct the type-bed of aluminum or aluminum alloy or some other metal or material having the characteristic of special lightness.

A difficulty arising in connection with attempts of the character just mentioned, lies in the fact that the light metals and materials available do not have the requisite properties to enable them to resist, without distortion or undue wear, the pressure which would be put upon them, in irregular places, by the type (when pressed on by the printing cylinder), or the rolling pressure exerted by the cylinder bearers or by the roller carriages upon which the type-bed makes its reciprocating movements. To overcome this, it has been proposed to apply, to the light metal of the type-bed proper, various supplementary members placed at locations where distortion or undue wear would otherwise occur. As examples of this, an iron or steel plate has been secured to the top face of the type-bed so as to receive the pressure exerted by the type, and iron or steel tracks have been secured beneath the type-bed, to run upon the roller carriages.

Such composite type-beds have been found to become warped and distorted so that the printing impression is not made with the requisite accuracy, because of the difference between the coefficient of expansion of the light metal of the type-bed proper and that of the iron, steel or the like employed for the supplementary members, particularly the tracks for running upon the roller carriages. It is desirable that these tracks be secured rigidly to the type-bed from end to end. Because of the difference in expansion and contraction, the tracks will cause the type-bed to bend or buckle slightly in one direction or the other when there is material rising or falling of the temperature with respect to the normal such as experienced on starting a press. This slight bending or buckling is sufficient to impair the excellence of printing that would otherwise be obtainable.

My invention makes it possible to provide a composite type-bed, in which the body portion is made of aluminum or other light metal or material such as molded plastics, synthetic resins or the like, and the supplementary pressure or wear-taking portions are made of iron, steel or the like, which will remain true regardless of considerable changes of temperature. In some instances, where it is not specially desirable that the supplementary portions be rigidly connected at all parts to the type-bed, I may attain this result by providing clearances for permitting contracting or expanding movement of these por-

tions relatively to the body of the bed. The tracks for running on the roller carriages, however, present a problem arising from the fact that it is desirable that they be secured rigidly to the type-bed from end to end. I attain the desired result by dividing these tracks up into a series of sections, each rigidly secured to the body of the bed and so short that expansion or contraction can have no appreciable effect, and 10 shaping the adjoining ends of adjacent sections obliquely, or otherwise irregularly, so that the rollers of the roller carriage can run from one section to the next section smoothly and without jar. By this means, I am able to obtain the increased press speed permitted by the use of an 15 exceptionally light type-bed while avoiding the disadvantage of variation in the trueness of the type-bed, which disadvantage has heretofore, so far as my knowledge goes, always accompanied attempts to employ a composite type-bed of the 20 general character to which reference has been made.

The same result may be accomplished in other ways to be described later and the broad principle of the invention may be utilized in securing to the bed various other supplementary portions such as the face plates, bearers, ink-plates, etc.

A type-bed constructed in accordance with my invention is described in detail herebelow, by way of example, and shown in the accompanying drawings, in which:

Figure 1 is a side elevation of the type-bed, with associated portions of the printing press shown diagrammatically;

Figure 2 is an end view;

Figure 3 is a fragmentary inverted plan, showing the portion of the type-bed adjacent one side thereof;

Figure 4 is a top plan of the type-bed;

Figure 5 is a section on the line V—V of Fig. 4;

Figure 6 is an enlarged section taken on the line VI—VI of Fig. 4;

Figure 7 is an enlarged section taken on the broken line VII—VII of Fig. 4;

Figure 8 is a view similar to Fig. 6 showing a modification;

Figure 9 is a view similar to Fig. 7 showing further modification;

Figure 10 is a partial plan view of a bed showing modified means for securing bearers thereto;

Figure 11 is a view similar to Fig. 6 showing a further modification, and

Figure 12 is a similar view showing a still further modification.

The type-bed herein shown is for use in connection with what is known as a two-color printing press, though the invention is, of course, equally applicable to the ordinary single-color press. The type-bed comprises a body portion 18, preferably of ribbed construction, of a length sufficient to accommodate the two type forms and their associated devices, and formed at the ends with shelves 11 for supporting the ink plates. This body portion is composed of aluminum or an alloy thereof or some other metal or non-metallic material, such as molded plastic, having lightness as a characteristic. The material in question may conveniently be referred to as "light material" hereafter. With the body portion are associated supplementary members for resisting pressure and/or wear, these members being composed of iron, steel or other metal or even non-metallic material capable of performing the desired function, which metal may conveniently be referred to as "wear-resisting material."

To the top of the body portion, along each longitudinal edge thereof, are attached a pair of bearers 12 for engagement by the circular bearers of the cylinders 13. The bearers 12 are of wear-resisting material and are held in place by screws 14 passing through holes (Fig. 6) which are larger than the screws, providing the clearances permitting relative movement between the bearers and the body portion when expansion or contraction takes place under temperature changes. The 10 bearers are formed with longitudinal recesses 15 underneath their inner edges, for receiving the longitudinal edges of the face plates to be described below.

Upon the shelves 11 of the body portion ink-plates 16, formed of wear-resisting material, are mounted. To provide for movement of these, laterally of the type-bed under temperature changes, their attachment is effected by clearance screws 17, as described in connection with 15 the bearers 12. In addition, keyways are provided in the ink-plates and body portion for receiving keys 18 (Fig. 7), the keyways being longer than the keys. Each ink-plate is formed with a longitudinal recess 19 underneath its inner edge, 20 for receiving the ends of the face plates now to be described.

Upon the top of the body portion 18 there are applied a pair of relatively thin face plates 20 formed of wear-resisting material. These face plates support the type-forms, one for each of the cylinders 13. The longitudinal edges and outer ends of the face plates are confined in the recesses 15 and 19 of the bearers 12 and ink-plates 16, respectively, clearances being provided between the outer edges of the face plates and the inner walls of the recesses, as shown in Figs. 6 and 7. The face plates are adjacent to each other, but slightly separated, at their inner ends, and are there secured to the body portion by means of a clamp 40 bar 21, held down by screws 22, the shanks of which pass through the space between the adjacent inner ends of the face plates. By this construction, it will be seen that the face plates can move in any direction relatively to the body portion, under the influence of temperature changes, all edges thereof except that engaged by the bar 21 being free. By using only one screw 22 instead of several as shown, the face plates may be anchored to the bed at substantially one point 50 only, permitting the utmost freedom of relative movement.

In the case of the bearers, ink-plates and face plates just described, a certain relative movement with respect to the body portion, such as would occur by reason of the various clamping means being overcome by the forces of expansion and contraction, is permissible. In the case of the roller tracks, however, such relative movement is usually undesirable because they are subjected to heavy pressures and reciprocate at high speeds. In meeting this difficulty, I divide each of the roller tracks (which are four in number) into a plurality of sections 23 each rigidly secured to the under side of the body portion of the type-bed. The sections of each track are disposed end to end, with a slight clearance between the adjacent ends. These adjacent ends are preferably, though not necessarily, cut obliquely (as indicated at 24, Fig. 3) so that the tracks can run smoothly upon the rollers of the roller carriages 25, without any jarring or shaking when the rollers pass from one track-section to the next. The track-sections are so short that their expansion 75

or contraction can have no appreciable effect upon the trueness of the type-bed.

Figure 8 illustrates roller tracks which are in one piece and are secured rigidly to the bed throughout their full length, but are permitted to have longitudinal movement relative thereto. As there shown, tracks 30 are dove-tailed into a bed 31. The tracks are secured against substantial movement relative to the bed by a single pin or screw (not shown). This mode of attachment permits free expansion and contraction of the tracks but utilizes tracks in one piece.

Figure 8 also shows a bearer 32 similarly dove-tailed to the bed 31. It is also held in place by a single pin or screw 32a and is otherwise free to expand and contract relative to the bed. The dove-tailed portions of both the tracks and bearer hold these parts against movement away from the bed.

Figure 9 illustrates the attachment of an ink-plate and a clamp bar to the bed by means similar to that just described. An ink-plate 33 has a dove-tail 34 fitting in a correspondingly shaped recess in the bed 31. The clamp bar 35 has a similar dove tail 36. The ink plate and clamp bar may be held against substantial longitudinal movement by a single pin or screw as in the case of the tracks 30 and bearer 32, without limiting expansion and contraction relative to the bed. The tracks 30, bearer 32, ink-plate 33, and clamp bar 35 need not be secured against longitudinal movement at any point if this is not desirable. Stop pins at opposite ends of these elements, spaced sufficiently therefrom to permit maximum expansion, will suffice to hold them in place without actually anchoring them at any one point. In such case, the face plates shown at 37 are free at all points to move in any direction in the plane of the bed.

Figure 10 illustrates bearers 38 formed in short sections, each of which is rigidly secured to the bed, for example by screws 39. This is simply another application of the principle of the sectional tracks 23.

Figure 11 shows another means of securing the face plate to the bed without precluding movement of the plate in the plane of the bed. As shown in Figure 11, a face plate 40 is held on a bed 41 by a bar 42 having a recessed edge. The bar 42 may be a bearer such as 12, or a clamp bar such as 21. A wedging strip 43 of rubber or other similar material, is disposed between the face plate and the overhanging edge of the bar 42. The face plate is thus held firmly in place on the bed but is permitted to move freely in all directions in the plane of the bed. The strip 43 need not be continuous as short lengths thereof along each edge of the bed will suffice to hold the plate in place.

Figure 12 is similar to Figure 11 but shows, instead of the rubber strip 43, one of a number of spring pressed plungers 44 seated in suitable bores in the overhanging edge of the bar 45, for yieldably urging the face plate against the surface of the bed.

In addition to employing a type-bed of light material with ink plates, bearers, tracks, etc., of iron or steel, I may make such parts of light weight material and secure them to a type-bed of iron or steel. I have in mind particularly, that relatively light weight beds may be fabricated from steel members suitably secured together as by welding. I may also employ wear-receiving parts such as those specified, of light material with a type-bed of similar material.

I also contemplate the use of wear-resisting members of molded plastic, or other light weight material, secured, as described herein, to type-beds of iron or steel or other lighter metal such as aluminum or its alloys.

It will be clear from the foregoing that the invention provides means for securing together various machine elements which, for functional reasons, are preferably composed of different materials having different coefficients of expansion. It is thus possible to design machines for a use under varying temperature conditions without the objectionable warping or distortion of composite parts to which reference has been made.

Although I have illustrated and described herein but a preferred embodiment of the invention with certain modifications thereof, it will be understood that changes in the construction and arrangement disclosed may be made without departing from the spirit of the invention or the scope of the appended claims.

I claim:

1. A printing press type-bed comprising a body portion formed of metal weighing less than steel and roller tracks formed of wear-resisting metal, each of said tracks being constituted by a plurality of sections secured to the body portion and disposed end to end, the adjacent ends of the sections being in proximity and disposed otherwise than at right angles to the length of the track.

2. A printing press type-bed comprising a body portion formed of metal, weighing less than steel and roller tracks formed of wear-resisting metal, each of said tracks being constituted by a plurality of sections secured to the body portion and disposed end to end, the adjacent ends of the sections being disposed in proximity and obliquely with respect to the length of the track.

3. In a printing press, the combination with a type-bed composed of a relatively light weight material, of a relatively thin face plate of wear-resisting material disposed on said bed, and means securing said plate on said bed including a bar extending along said plate, the edge of said bar having an edge recess adapted to receive the plate edge, with sufficient clearance between said plate and said bar to permit differential expansion and contraction thereof.

4. A printing-press type bed comprising a body portion of light-weight metal and roller tracks formed of wear-resisting metal having a coefficient of thermal expansion differing from that of the metal of the bed body, each of said tracks being constituted by a plurality of sections secured to the body portion and disposed end to end, the adjacent ends of the sections being in proximity and overlapping so as to give the effect of a continuous track.

5. A printing-press type bed comprising a body portion of light-weight metal and roller tracks formed of wear-resisting metal having a coefficient of thermal expansion differing from that of the metal of the bed body, each of said tracks being constituted by a plurality of sections secured to the body portion and disposed end to end, the sections being so short that the differential thermal expansion or contraction of the metal of the bed and the tracks does not cause warping of the bed even through the sections are rigidly connected to the bed.

6. In a printing press, the combination with a type bed composed of a relatively light-weight material, of an ink plate composed of a material having a coefficient of thermal expansion differ-

ent from that of said light-weight bed material and extending across the bed at an end thereof, means for locking the ink plate against movement longitudinally of the bed while permitting movement laterally thereof, and means for securing the ink plate against the bed having provision for limited lateral movement therebetween to compensate for differences in thermal expansion.

10. 7. In a printing press, the combination with a type bed composed of relatively light-weight material, of a bar of wear-resisting material having a coefficient of thermal expansion different from that of the light-weight bed material dovetailed to the bed so as to lock the bar against movement in all directions except longitudinally thereof, and means for locking the bar against longitudinal withdrawal from the bed while permitting longitudinal thermal expansion thereof with relation to the bed.

8. In a printing press, the combination with a type bed composed of relatively light-weight material, of a bar of wear-resisting material having a coefficient of thermal expansion different from that of the light-weight material, means for securing the bar to the bed and locking it against all movement except movement longitudinally of the bar, and means for preventing longitudinal withdrawal of the bar from the bed

but permitting differential longitudinal expansion of the bar with relation to the bed.

9. In a printing press, the combination with a type bed composed of a relatively light-weight material, of a thin face plate of wear-resisting material having a coefficient of thermal expansion different from that of the light-weight material disposed on the bed, and means for confining the face plate including bearers along the sides of the bed and an ink plate at one end of the bed, and means at one edge of the face plate for anchoring it to the bed, there being provision for relative movement between the face plate and its confining means to permit differential thermal expansion between the face plate and the bed.

10. In a printing press, the combination with a type bed composed of relatively light-weight material, of a thin face plate of wear-resisting material having a coefficient of thermal expansion different from that of said light-weight material disposed on the bed, means for confining the face plate on the bed including bearers along the sides of the bed and an ink plate at one end of the bed, and means for anchoring the face plate at one point, there being provision for differential movement between the face plate and its confining bearers and ink plate.

SAMUEL A. HUFFMAN.
